and in Italy February 17, 1931

10 Claims (Cl. 244—19)

The present invention relates to improvements in helicopters that is to those flying machines which by means of propellers mounted on vertical, or nearly vertical, shafts, are capable of maintaining themselves still in the air, and to lift or to lower themselves vertically, and also to move in the horizontal as well as an oblique direction.

A special feature of the invention consists in a control device for the blades of the propellers, 10 which is capable of causing the variation of the angle of incidence, either automatically or at will of the pilot, so as to maintain unaltered or to vary at will the lifting power of the propeller, both in amount and in direction, and also in order 15 to give rise to a torque lying in a plane normal to the axis of rotation, which may be varied at will both as to amount and direction of rotation.

It is thus possible to cause the apparatus to rise or to fall, or to shift it in the horizontal or 20 an oblique direction, or to incline it in the longitudinal or in the transversal directions, (and also allow the correction of the eventual list) and it is also possible to cause the apparatus to rotate in the horizontal plane so as to guide it in the 25 direction desired, and also to veer it in any desired manner.

The said mechanism also makes it possible to overcome the effects of the unsymmetrical character of the thrust of the air on the blades, when 30 the apparatus has assumed a rapid movement of translation.

Lastly, the mechanism renders it possible, even when the motor does not work, to instantly increase the lifting thrust of the propellers, by 35 drawing upon the force of inertia stored in it, and consequently provides for an effective braking of the descending movement when landing.

With regard to the variation of the direction of the lifting thrust, the said mechanism is based 40 on the fundamental principle consisting in that, if to a propellers' blade which is hinged to the hub, the angle of incidence is varied periodically during one revolution (which would have the effect of varying periodically the relative aero- 45 dynamical thrust) the said blade performs oscillations, which, combining with the rotary movement will have the effect of changing the plane of rotation of the blade, and consequently also of the direction of the lifting thrust.

With regard to the automatic control of the 50 amount of the lifting thrust, the said mechanism can be actuated in three different ways, viz.; by utilizing, for the automatic control, the inclination which the blades assume under the action 55 of the centrifugal force and the aerodynamic re-

actions, or by taking advantage of the moment of the said aerodynamic reactions with respect to the longitudinal axis of rotation of each blade, or also by utilizing the variations of the axial thrust of the propellers.

In all these cases, it is preferable that the blades should possess a small moment of inertia with respect to the longitudinal axis of rotation (and consequently a considerable elongation), and it is necessary also to construct the blades 65 with such a profile that the resultant centre of the thrust of the aerodynamic reactions may not be shifted, or only slightly shifted in the transverse direction when the angle of incidence of the blade is varied.

When the blades satisfy the above mentioned conditions, it is easy to provide for their control by following either the first, the second or the third methods above mentioned, as will appear more clearly from the following detailed description, and with reference to the annexed drawings, which illustrate schematically a helicopter made according to the present invention considered as a whole, and includes the construction and arrangement of the parts composing it.

Fig. 1 shows a side elevation of the complete helicopter resting on the ground.

Fig. 2 shows one way of connecting the motor with the propellers.

Figs. 3 and 4 show respectively in vertical axial section and in plan elevation one way of articulating the blades to the hub.

Figs. 5, 6, 7 and 8 show various sections of the blades.

Figs. 9 and 10 show schematically two different forms of construction of the device for the control of the blades.

Figs. 11 and 12 show schematically two different arrangements for connecting the motor to the propellers.

Figs. 13 and 14 illustrate in perspective and in detail, respectively, of the controlling means by which to tip and adjust the propeller blade adjusting rings.

As may be seen in Fig. 1, which shows the helicopter in complete form, including a body 1 in which are arranged the places *a* for the passengers, and in front of these, the seat 3 for the pilot; the motor 4 being disposed behind.

The body or hull is provided with elastic means 5 and 6 for landing, which, as shown in the drawings, may take the form of skids. No wheels are required as the apparatus has no need to run rapidly on the ground before rising, although

wheels may be provided in order to facilitate the shifting of the apparatus on the ground.

The apparatus may also be arranged to rise from or descend upon the water, in which case 5 suitable floats may be provided.

The body is also provided with fixed tail stabilizing surfaces 7 and 8, the object of which is to improve the stability of flight during the 10 horizontal movement of the apparatus; whereby the horizontal plane 7 can eventually be made to oscillate and to be controllable so as to provide to the centering of the apparatus, and to the variations of the longitudinal trim during the horizontal travel of the apparatus.

15 Also the vertical plane 8 may eventually be controlled, so as to be of assistance in turning.

In addition, the body may also be provided with small wings which prove to be useful during the horizontal course, as they contribute to sustaining and improving generally the flying qualities 20 of the apparatus.

The body is provided with a back fin 9, which if suitably provided with windows, can be used together with the body, as an inner guide, the 25 principal duty of which being that of supporting the essential flying devices of the machine.

These devices comprise two propellers 10 and 11, co-axial with each other, rotating in opposite directions and driven by the motor 4.

30 In Fig. 2 is shown by way of example, a motor of the star type cooled by air by means of the fan 12 mounted on the main shaft 13 of the motor; it is however possible to use other types of motors and other systems of cooling.

35 When using a motor cooled by air supplied by a fan, it is necessary to convey and direct the air current accurately on the radiating ribs of the cylinders 14, by guiding the fluid streams by means of metal plates 15 suitably shaped (as 40 shown schematically in Fig. 2) so as to obtain the desired result with the least possible consumption of power.

Fig. 2 shows the case in which a motor is fitted obliquely, so that the shaft 13 transmits the movement 45 directly to the first propeller 10 by means of a speed reducing gearing formed by the pinion 16 and the toothed wheel 17.

The propeller 10 is provided with a hollow hub 18 revolving on the fixed tube 19 acting as a bearing, and transmits the movement to the second propeller 11, which is also mounted on a hollow hub 20, said transmission comprising the two toothed wheels 21 and 22 and the pinions 23.

It is also possible to adopt other means for 55 transmitting the movement, such alternative means being shown by way of example in the Figures 11 and 12.

In the arrangement shown in Fig. 11, the shaft 60 13 of the motor 4 drives the vertical shaft 56 by means of a pair of conical wheels 55 (which can be omitted when the motor is placed with the vertical axis below the propellers), the said vertical shaft being provided, in correspondence with each propeller, with a pinion 57 which engages 65 with one, two, three or more pinions 58 mounted on small shafts 59 whereon are also fixed other pinions 60 all of which in their turn engage with a toothed crown 61 fixed on the propeller.

In the arrangement shown in Fig. 12, the shaft 70 13 of the motor 4 drives, eventually through a first speed reducer 62, the vertical shaft 63, which causes the rotation of the first propeller through the pinion 64, the satellite pinions 65 and the toothed crown 66 connected to the said propeller, 75 and it also causes the rotation, in the opposite

direction, of the second propeller, by means of another pinion 67, and other satellite pinions 68, (the cage of which is connected to the second propeller) and of a toothed fixed crown 69.

In order to allow the free rotation of the propellers, even when the motor is cut off or clogged, and in order to be able thus to descend when the propellers rotate freely by taking advantage of their action as parachute, it is necessary to introduce between the motor and the propellers a disconnecting device or a free wheel arrangement 24 which is schematically shown in Fig. 2.

The propellers may be provided with a variable 8 number of blades, for example 2, 3, or 4, which 9 may have any suitable shape; these blades are attached to the hub by means of hinges 25, 26, 27 and 28 which allow them to set themselves in the direction of the resultant of the centrifugal force and of the axial thrust; in this way the bending moment on the blades is eliminated or 10 at least greatly reduced.

The said blades are in addition free to rotate 11 round a longitudinal axis which is approximately parallel to the leading edge, because they must be able to change their angle of incidence with 12 respect to the relative wind.

It is also advantageous to allow the blades to oscillate slightly in their plane of rotation, so as to eliminate or reduce the alternate movements 13 which develop in that plane, which are caused by the combined effect of the rotation and of beatings of the blades, or by the combined effect of 14 the rotation of the blades and the movements of the apparatus.

It may however be preferable and more convenient 15 from an aerodynamical point of view to use stops (eventually of the elastic type) inserted in the hinges. This causes naturally the production of bending strains in the blades when 16 they are at rest, which can however be easily 17 maintained within practical limits by allotting the blades convenient dimensions.

Moreover the propellers, according to the present invention, are also provided with a control 18 mechanism of the blades, which allows the variation 19 of the angle of incidence, either automatically 20 or under the control of the pilot, so as to maintain unaltered or to change at will the lifting power of the machine, both in amount and in direction, as before stated, and also to change at will 21 the resisting torque of the propeller; the said actions being required to produce the vertical, oblique and horizontal movements of the apparatus, and to cause it to veer in any direction required. The said control mechanism may assume 22 many different forms, by varying the shape, the arrangement and the working of the parts composing it, while obtaining the same result.

Amongst the various possible forms of construction, some are described hereinafter by way 23 of example.

A first form is shown in Figs. 3, 4, 5, 6, 7 and 8, in which the blades 29 and 30 are free to revolve and to oscillate by means of the thrust bearings 31 and 32, and of the radial bushes 33 and 34. In 14 the form shown by these figures it is supposed to do away with the third hinge which allows the blades to oscillate in the plane of rotation.

The bushes 33 and 34 are fixed on the hubs 35 and 36 which rotate round the tube 19 by 14 means of the bushes 37 and 38.

The longitudinal axis of rotation of each blade is arranged to pass through the centre of thrust of the blade (which as above said does not shift transversally to the blade).

The blades are moreover constructed and counterweighted so that their centre of gravity is also placed on the axis of rotation.

In the conditions above described, whichever 5 be the arrangement or the incidence of the blades, there are no torsion couples which have the tendency of causing them to revolve round their own axes.

The blades are provided with extensions 39 and 10 40, which are connected to the two rings 43 and 44 by means of the links 41 and 42.

Supposing in the first place that the said two 15 rings are invariably mounted on the hubs 35 and 36, the automatic control of the blades acts in the following way.

If for example an axial wind begins to blow, which has the tendency of increasing or decreasing 20 the angle of incidence of the blades, these will be solicited to rise or fall, in order to re-establish the equilibrium between the centrifugal and the axial forces; however, as the links 41 and 42 are fixed (Figs. 4 and 5) and are also connected 25 to the blades eccentrically with respect to the longitudinal axis of rotation, they force the blades to rotate round said axis thus bringing back the incidence of the blades to approximately the original value. It will now be evident that the mechanism above described operates in such a way as 30 to maintain almost unaltered the moment of the axial thrust acting on each blade, for a given velocity of rotation of the propeller, and as the longitudinal excursions of said thrust, are of small amounts, it may be stated that said mechanism maintains on each blade the axial thrust 35 almost unaltered.

A similar correction takes place when a transverse wind occurs, in which case the thrust on the blades during one rotation, would vary greatly 40 on account of the continuous variation of the speed and of the incidence of the relative wind; this however causes beatings of the blades, which are taken up by the links above said and are connected into angular shifting of the blades, which contain within small limits the variations of the 45 thrust, or at least, as it is found by the mathematical treatment of the problem, they cause to vanish the first harmonic of the variable thrust.

In the conditions of flight above described it is thus apparent, as before mentioned, that it 50 is convenient that the blades should possess a small moment of inertia, so as to allow them to perform their necessary continuous angular oscillations with very small torsional momentums.

If on the other hand the rings 43 and 44 are 55 not fastened to the hubs, but by means of two rows of balls, are simply connected with the sleeves 45 and 46 which do not revolve with the propellers but are subjected to axial and angular movements controlled by the pilot, it becomes 60 thus possible to vary at will the conditions of flight. In other words, if the said sleeves are lifted or lowered simultaneously, the conditions of equilibrium of the blades will be varied, and consequently also the resultant axial thrust, 65 thence the apparatus is enabled to travel upwards or downwards vertically.

If the control attachment of the sleeves is 70 differential, viz; when one is raised the other is lowered, the resultant thrust remains the same but distributes itself differently between the two propellers, which in this case have to absorb different driving couples; the resultant of this is the formation of a differential couple which forces the apparatus to rotate in an horizontal 75 plane.

Finally if the sleeves 45 and 46 are shifted angularly either in the longitudinal or in the transverse directions, it will be apparent that the said arrangement will cause the periodical variation of the angle of incidence of the blades 80 at each revolution, which fact, as already mentioned at the beginning of this description, will cause the blades to oscillate, and will also change the position of the plane of rotation of the two propellers, which will be forced to rotate in planes parallel to each other and obliquely with respect to the tube 19; the resultant thrusts will be shifted and they will become inclined, giving rise to moments with respect to the centre of gravity of the apparatus, and will cause this latter to incline in the longitudinal or transversal plane. In particular, if the apparatus is inclined forward and is maintained in such position, the lifting thrust acquires an horizontal component which causes a movement of translation. 90 95

With regard to the control of the sleeves 45 and 46, Figs. 3 and 4 show that each sleeve is controlled with three rods 47 (and 48) disposed into the tube 19. 100

It is also possible to cause the rods 47 and 48 to descend outside the tube 19 (when this is used as the shaft for the rotation of the blades, as shown in Figs. 11 and 12) providing of course this tube with suitable expansions in correspondence 105 with the propellers, so that the rods 48 may be carried without hindrance through the central part of the propeller 10.

Of course, the control of the rods 47 and 48 may be effected in many different ways; one of 110 which consisting in connecting the said rods to discs or rings which by suitable transmission may be controlled by the pilot either axially or angularly (said transmissions may also be made to reach directly the sleeves 45 and 46). 115

Fig. 13 particularly illustrates the connection of the rods 47 and 48 to the slidable rings 70 and 71, respectively, said rings, as already indicated, being subjected to axial and angular movements. In order to render such movements feasible, the 120 rings are mounted on the spherical joints 72 and 73, which latter in turn are fixed upon telescopic tubes 74 and 75, respectively, these tubes being adapted to slide axially the rod 76 secured to the housing 77. 125

The mentioned slidable rings may be controlled by the pilot by means of appropriate transmission devices, such as for example, a control lever 78, a foot lever 79, and a lifting lever 80. If the control lever 78 which is mounted on a spherical pivot 82 and is therefore shiftable in all directions, should be shifted forwards or backwards by the pilot in the direction indicated by the arrow 81, he can impart angular movement to the rings 70 and 71 by means of 135 the rods 83, thus producing the angular movement of the rings 45 and 46, through the connecting rods 47 and 48. This angular movement in turn produces the alternate and periodical oscillations of the blades round their longitudinal axes, which, owing to the aerodynamical reactions already described, produce the inclination of the rotating planes of the propeller and consequently also the variation of the longitudinal trim of the aircraft, as well as its horizontal trim. 140

If, on the other hand, the control lever 78 is moved in the direction indicated by the arrow 84, the pilot, through the transmission device 85, 86, 87, 88, 89 and 90, causes the angular shifting of the rings 70 and 71 in a plane 145 150

which is normal to the plane in which the said rings would oscillate when moved by the rods 83, the said angular shifting being similarly transmitted to the rings 45 and 46 by means of the rods 47 and 48. The resultant of said movement is a transversal inclination of the rotating planes of the propellers and consequently the variation of the transversal trim of the aircraft.

10 When the pilot with his foot depresses the end of the lever 79 which is pivoted at 91, he will cause this lever to oscillate in a horizontal plane, this oscillation, by means of the transmission formed by the rods 92, the two bent levers 94, 15 pivoted at 95, and the small connecting rods 96, will cause the axial sliding in opposite directions of the telescopic tubes 74 and 75. As a consequence there will occur a shifting of the rings 70 and 71 which are fixed on the said tubes, 20 which latter are subjected to oppositely directed axial movements, so that while the rods 47 are lifted, the rods 48 are lowered, these movements being followed respectively by the collars 45 and 46, so that the angles of attack of the two propellers, as already described, are modified, the 25 resulting dissymmetry of the horizontal couples of reaction causing the apparatus to rotate in the horizontal plane.

Fig. 14 shows the compensating spring 51 adapted to counteract the lift thrust of the blades, and the means for controlling it. This spring will be deformed more or less according to the stresses transmitted to it by the rods 47 and 48, thus causing the movements of the casting 77 and consequently, also movements of the rods 47 and 48, for ensuring, as already stated, the automatic control of the sustaining thrust.

In order to set the apparatus into a rising or falling condition, it will be necessary to adjust 40 the compression of the spring 51 so as to change the equilibrium trim at will, and in order to accomplish this it will be sufficient to operate the lifting control 80, which is connected to the spring 51 by means of the connecting rods 97 and 99 45 and the lever 98, instead of said control 80 being directly connected to the box 77 by means of the same connecting rods as shown in Fig. 13.

To the members above described, it will be sufficient to add the motor handle, or this may 50 be provided with an automatic regulator for maintaining an even speed of rotation of the propellers even when the load varies; or else the pilot may have at its command a handle for changing the position of equilibrium of the said 55 regulator and consequently for controlling the speed of the propellers.

A second form of construction can be attained by applying the second of the arrangements above mentioned for the control of the blades.

60 If the longitudinal axis of rotation of the blades is placed a little forward with respect to the centre of thrust of the aerodynamic reactions (viz, between the leading edge and the said centre of thrust) and the blades themselves are counter-weighted so that the centre of gravity lies instead on the axis of rotation (or in any case be nearer to this axis than the centre of pressure) every blade will be constantly affected by a yawing moment which, supposing the centre of thrust 65 to be fixed, results in becoming proportional to the said pressure.

Assuming that the mechanism of control of the blades is similar to that shown in the Figures 3, 4, 5, 6, 7 and 8, having however the bushes 75 31, 32, 33 and 34 so close to the axis that the ex-

tensions 39 and 40 have a very small length, the oscillations of the blades will not produce in this case any perceptible variations in the incidence of the said blades, but the yawing moment of the blades will be transmitted to the rods 47 and 48 through the links 41 and 42 and the sleeves 45 and 46.

If therefore (Fig. 9) the said rods 47 and 48, after traversing a control box 49, engage upon a flat disc 50, which is free to move axially, on this disc there will be developed a force which will be proportional to the sum of the yawing moments of the blades, viz. proportional to the sum of the lift thrust of the blades, which force can be equilibrated or counteracted by means of a spring 51, or by other equivalent means, based for example on the centrifugal force developed.

If therefore, because of the axial wind the thrusts on the blades increase or decrease, also the yawing moments will increase or decrease accordingly, and the resultant force conveyed by the rods 47 and 48 on the disc 50 will become greater or smaller than the reaction exerted by the spring 51; the disc 50 will consequently be shifted and the blades will revolve until the thrust 100 is re-established.

Of course, by adjusting the compression of the spring, the conditions of equilibrium can be altered as required and consequently the apparatus rises or falls, shifting then, by means of 105 the control box 49, the rods 47 in a direction opposite to the rods 48. Thus it is possible to distribute the driving couples between the propellers, and consequently the whole apparatus can be made to rotate. Furthermore, by shifting the 110 rods 47 and 48 through unequal amounts (always by means of the control box 49) it is possible to incline angularly the sleeves 45 and 46, and consequently the planes of rotation of the propellers and the direction of the lifting force can be set 115 obliquely.

Finally it is also possible to operate the control of the blades by a third method which is based on the utilization of the variations of the axial thrust.

If the tube 19 (Fig. 10) supporting the propellers is connected to the body or hull of the apparatus not rigidly but through an elastic system 52 (comprising for example a single spring and a pile of rings mounted concentrically with 125 respect to the tube 19 and enclosed within a tube 53 fixed to the body) to any variation of the resultant lift thrust, there will be a corresponding axial movement of the tube 19, caused by the yielding of the elastic system.

Supposing now that the blades are controlled by the above described link rods 41 and 42, attached at one end very close to the hinges of the blades themselves and the other end to the rings 43 and 44, controlled by the sleeves 45 and 46 and by the rods 47 and 48.

If the rods 47 and 48 are fixed to the body 53, as every variation of the lift thrust produces, as stated before, a shifting of the tube 19, a relative movement is thus produced which alters the angle 140 of incidence of the blades, and this is sufficient to restore the equilibrium, in the same way as described in the second form of construction.

When, on the other hand, the rods 47 and 48 are not rigidly fixed to the body, but are led to a control box 54, fixed on the body, similar to the box shown in Fig. 9, it is possible to perform all the operations that may be desired; in particular, when the rods 47 and 48 shifting together, the inclination of all the blades is changed simulta- 150

neously. The said movement has the effect of varying the value of the axial thrust which gives rise to a compensating movement of the tube 19, but as the reaction of the elastic means changes when its state of compression or tension is varied, the equilibrium becomes restored for a slightly different value of the axial thrust, and by continuing the manual operations, the desired variation of thrust can be attained.

10 In the system now described it is of course necessary that the tube 19 be attached to the body so as to be free to slide but not to rotate, so that it may also transmit the torsion moments which are obtained by displacing the rods 47 in the contrary direction to the rods 48.

15 It is moreover necessary that in the transmission between the motor and the propellers, a shaft of the telescopic type or even of the cardan jointed type (if obliquely disposed), is inserted, so as to ensure the transmission of power in spite of the relative displacements occurring between the propellers and the body, unless it is preferred to connect the motor rigidly to the system of the propellers and to elastically connect the whole 25 apparatus to the machine body.

I claim:

1. A helicopter provided with a shaft and fitted with two coaxial propellers revolving in opposite directions and having blades which are provided 30 with an articulation allowing the blades to oscillate in a plane passing through the center of said shaft and automatically adjust themselves in the direction of the resultant of the centrifugal force combined with the aerodynamical thrust, which 35 propeller blades are rotatable about their longitudinal axes, and on each propeller are connected to a ring which is individual to the propeller and individually movable relatively to the propeller shaft in order to produce variations of the angle 40 of incidence of the blades, whereby to vary the value of the lifting thrust, and means for moving each of said rings, which latter, in uneven or dissimilar setting, cause the formation of a differential couple for veering the machine as a whole, and 45 in even or similar setting, cause a periodic variation of the angle of incidence of the blades so as to oscillate the latter and thereby produce inclination of the plane of rotation of the propellers and vary the direction of the lifting thrust thereof, 50 there being means for rotating said propellers.

2. A helicopter according to claim 1, having automatic means for moving the rings pertaining to the propellers.

3. A helicopter according to claim 1, having controlled means for moving the rings pertaining to the propellers.

4. A helicopter according to claim 1, having link rods connecting the blades of the propellers with movable rings controlling the angle of incidence of said blades, which link rods produce the rotation of the blades about their longitudinal axes by the effect of the variations of the light thrust, and as a result produces the automatic variation of the angle of incidence in the proper direction for maintaining the axial thrust of the apparatus practically constant.

5. A helicopter according to claim 1, wherein the centre of thrust of the propeller blades is disposed outside their longitudinal axes of rotation, a disk associated with the helicopter capable of assuming solely axial displacements, axially sliding control rods disposed against said disk and

communicating stresses and strains thereto tending to displace the same, and regulatable means simultaneous exerting an opposing force on said disk, so that axial sliding of the rods and automatic control of the propellers is produced by the resultant force exerted on the disk, there being other control devices for obtaining other movements of the helicopter.

6. A helicopter according to claim 1, and thrust bearings controlling the rings which regulate the angle of incidence of the propeller blades, together with two groups of control rods disposed along the shaft of the propellers, there being control devices for operating and moving said control rods.

7. A helicopter according to claim 1, provided with a tube carrying the propellers, means elastically suspending the body of the machine to said tube in order to actuate the automatic control of the rings during flight, and means cooperating therewith for increasing or decreasing the axial thrust in order to vary the length and thereby produce concordant rotation of the blades about their longitudinal axes, there being additional means for further controlling the operation of the 100 machine.

8. A helicopter according to claim 1, wherein the body of the machine carries the means for rotating the propellers in the form of a motor having a shaft, the propeller shaft being common 105 to both propellers which are rotatable about the same while one propeller is mounted above the other, a hollow hub on the lower propeller provided with a gear thereon, a pinion on the motor shaft meshing with said gear to directly drive 110 said lower propeller, a hollow hub on the upper propeller also having a gear thereon, and means including additional gearing communicating rotation to said latter gear and the upper propeller from the gear of the lower propeller and driving 115 the upper in the opposite direction from the lower propeller.

9. A helicopter according to claim 1, wherein each propeller is provided with a hollow hub having a crown gear, the means for driving the propellers consisting of a motor having a shaft, and the propeller shaft being rotatable within the propeller hubs, and means communicating rotation from the motor shaft to the propellers including gears rigid on said propeller shaft meshing with pinions on one end of rotary spindles carrying a pinion on their other ends meshing with the crown gears of the propeller hubs, and means driving said propeller shaft directly from said motor shaft.

10. A helicopter according to claim 1, wherein the means for rotating the propellers consists primarily of a motor having a shaft, a hollow hub upon each propeller surrounding the propeller shaft which is vertically disposed and driven by 135 said motor shaft, a pinion connecting the motor shaft with said vertical propeller shaft, which propeller shaft communicates its rotation to one propeller by means of a pinion, one or more satellite pinions and a crown gear engaging with said 140 one propeller, and similarly communicates its rotation to the other propeller by means of another pinion, a second group of satellite pinions mounted in a casing which is connected to said other propeller, and a fixed crown gear.

FERDINANDO BORDONI.
